Primary Examiner — Prabhakar Deshmukh(74) *Attorney, Agent, or Firm* — Theodore Heske, III(57) **CLAIM**

The ornamental design for a linear shaped digital display, as shown and described.

DESCRIPTION

FIG. 1 is a perspective view of a linear shaped digital display showing my new design;

FIG. 2 is a rear perspective view thereof;

FIG. 3 is another rear perspective view thereof;

FIG. 4 is a front elevation view thereof;

FIG. 5 is a rear elevation view thereof;

FIG. 6 is a left elevation view thereof;

FIG. 7 is a right elevation view thereof;

FIG. 8 is a top plan view thereof; and,

FIG. 9 is a bottom plan view thereof.

The broken lines and any dashed lines of FIG. 1 through FIG. 9 are for illustrative purposes only and form no part of the claimed design.

1 Claim, 3 Drawing Sheets(56)
